UNITED STATES PATENT OFFICE.

HENRY NORBERT BERNIER, OF ST. EUGENE, DE GUIGUES, QUEBEC, CANADA, ASSIGNOR
OF ONE-HALF TO JULES DE FROY, OF TIMMINS, ONTARIO, CANADA.

FUNNEL.

1,353,712.

Specification of Letters Patent. Patented Sept. 21, 1920.

Application filed April 29, 1919. Serial No. 293,390.

To all whom it may concern:

Be it known that I, HENRY N. BERNIER, a subject of the King of Great Britain, residing at St. Eugene, de Guigues, Quebec, 5 Dominion of Canada, have invented new and useful Improvements in Funnels, of which the following is a specification.

This invention relates to funnels for use in filling the gasolene tanks of automobiles, 10 cans, bottles, jugs and other containers so desired, and the object of the same being to provide a device of this class which is simple in construction, durable and efficient in use, and one wherein provision is made of 15 an indicator operated automatically when the container is filled consequently preventing waste of the contents thereof.

With the above and other objects in view, the invention consists in novel features, 20 details of construction and combination of parts which will hereinafter be more fully set forth, illustrated in the accompanying drawings and pointed out in the appended claim.

25 Figure 1 is a vertical sectional view.

Fig. 2 is a transverse section taken on line 2—2 of Fig. 1.

Fig. 3 is a transverse section taken on the line 3—3 of Fig. 1 and,

30 Fig. 4 is a transverse section taken on line 4—4 of Fig. 1.

In the practice of my invention I provide a funnel device comprising the usual tapered body portion 5, the smaller end of 35 which is provided with the usual tubular extension 6 adapted to pass through the apertures or filling openings of gasolene tanks or the like containers.

In the lower end of this tubular extension 40 6 is provided diametrically disposed apertured lugs 7 in which slidably operate rods 8 carrying at their extremities a weight or float 9. While rigidly secured to and extending from the lower end 7 of this tubular extension is a protector or cap 10, the purpose of which will hereinafter more fully described as the description of the invention 45 is proceeded with.

The character 11 denotes a transverse supporting bar mounted within the body 5 of the funnel and provided at a point in its length with a depending substantially V-shaped ear 12 having pivoted therein a link 13 and from which the valve 14 is suspended. The stem 15 of this valve is piv-

oted as at 16 to one extreme end of the link while an operating rod 17 is pivoted to the opposite extreme end of the link. The lower end of this operating rod 17 is connected as at 18 with the float 9. To prevent 60 the contents when poured into the channel from seating the valve 14 on its seat 19, use is made of a protecting plate or cap 20 rigidly supported within the body of the funnel adjacent the point of formation of 65 the extension 6 therewith and further at a point above the valve seat 19. A series of apertures 21 is provided in the superposed guide bars 22 and certain of said apertures 70 slidably receive the lower end of the stem 15 of the valve while the remaining apertures of these guide bars perform the function of guiding the operating rod 17 in its movement. Use is made of a coil spring 23 which embraces the upper end of the rod 75 24 and to facilitate the guiding of said rod the same passes through an aperture 25 provided in the supporting bar 11. The function of spring 23 is to hold rod 24 elevated.

In briefly describing the operation of the 80 invention and assuming the tubular extension 6 is inserted within the opening of a container or the like, upon the container assuming its filled position, the liquid engaging with the weight or float 9 will elevate the latter and in turn rock the link 13 which forces the valve 14 into engagement with the seat 19, and the valve is held in closed position by the engagement of the thumb of the operator with rod 24. At this 85 point it may be said that the protector 10 prevents the liquid when poured into the container from marring or damaging said float.

From the foregoing description, taken in 90 connection with the accompanying drawings, the advantages of construction and the method of operation will be readily apparent to those skilled in the art to which the invention relates, and while I have described 100 the principles of operation of the invention together with the device which I now consider to be the best embodiment thereof, I desire to have it understood that the device shown is merely illustrative and that such 105 changes may be made when desired as are within the scope of the appended claim.

Having thus described my invention what I claim as new, is:—

A funnel comprising a body provided 110

with a tubular extension, a valve seat at the point of intersection of the extension with the funnel, a float slidably suspended below and on the lower end of said extension, a 5 transverse supporting bar arranged in the body of the funnel and provided at one side of its intermediate portion with a depending V-shaped ear, a link pivotally mounted in the apex of the ear for rocking movement, a valve having a stem, a protector arranged in the funnel body at a point between the point of intersection of the tubular extension with the funnel body and said supporting bar, one end of said stem being

slidably mounted through the protector and having pivotal connection with one extreme end of the link, an operating rod carried by said float operating to one side of the protector, and having pivotal connection at one end to the opposite end of said 20 link, a manually operative rod connected with the valve, a spring embracing the rod for retaining the valve in an elevated position, said rod operating in an aperture of the bar and an aperture of the protector 25 plate.

In testimony whereof I affix my signature.

HENRY NORBERT BERNIER.
